UNITED STATES PATENT OFFICE.

CURRAN S. BENTON, OF PORT HURON, MICHIGAN.

BEAN SEPARATOR.

Application filed April 18, 1927. Serial No. 104,865.

The invention relates to a separator and more particularly to the class of gravity separators for use in separating imperfect beans, peas, grains and seeds from perfect beans, peas, grains and seeds, or the like.

The primary object of the invention is the provision of a separator of this character, wherein the separation of perfect and imperfect beans, peas, grains or seeds will be automatically effected by gravity, in the use of a harmless liquid agent, whereby a large percentage of the imperfect beans, peas, grains or seeds can be floated off from the perfect beans, peas, grains or seeds.

Another object of the invention is the provision of a separator of this character, wherein a plurality of receptacles are nested, one within the other and through the use of a harmless liquid agent the perfect and imperfect grades of commodities in a batch can be automatically separated by gravitation and such grades of commodities readily and conveniently removed after the separating operating operation from the liquid solution or agent without any possibility of agitation to the solution which would have a tendency to change the gravity of the same.

A further object of the invention is the provision of a separator of this character, wherein the construction thereof is novel in form as the units of the device are readily separable one from the other, to permit the convenient extraction of the best or better grades of commodities when introduced therein, as the grades of such commodities will be automatically separated into independent batches, the separation being individual in character in contradistinction to a continuous operation of the well known separators, the good and poor commodities being positively separated from each other in the use of the machine or device.

A still further object of the invention is the provision of a separator of this character, wherein a batch of commodities is introduced therein, to effect the positive separation of the good and poor grades of commodities from each other, with dispatch and without the necessity of agitation, the separated grades of commodities being readily extracted with dispatch and without affecting the liquid agent contained within the device, the liquid agent or solution being usable for a maximum length of time and without liability of deteriorating effect on the better or good grade of commodity separated.

A still further object of the invention is the provision of a separator of this character, which is extremely simple in construction, thoroughly reliable and efficient in its purpose, strong, durable, sanitary, and inexpensive to manufacture and operate.

With these and other objects in view, the invention consists in the features of construction, combination and arrangement of parts, as will be hereinafter more fully described in detail, illustrated in the accompanying drawings showing the preferred embodiments of the invention, and pointed out in the claims hereunto appended. It is to be understood, however, that changes, variations and modifications may be made in the separator, as come properly within the scope of the appended claims without departing from the spirit of the invention or sacrificing any of its advantages.

In the accompanying drawings:

Figure 1 is a perspective view of the assembled units of the separator constructed in accordance with the invention, the forward or front walls of the units of the separator being partly broken away.

Figure 2 is a vertical broken transverse sectional view through the separator.

Figure 3 is a sectional view on the line 3-3 of Figure 2 looking in the direction of the arrows, the shutter mechanism of the separator being shown by full lines closed and by dotted lines in open position.

Similar reference characters indicate corresponding parts throughout the several views in the drawings.

Referring to the drawings in detail, the separator comprises an outer tank A, the same being made preferably from sheet metal and of the required size and shape to give maximum capacity thereto. This outer tank A is opened throughout its top and has an imperforate bottom 10, front and rear walls 11, and side walls 12, these walls being of uniform height. Removably nested within the outer tank A and suitably spaced from the inner faces of the bottom, front, rear and side walls 11 and 12, respectively, is an intermediate tank B, which is formed with a wire mesh or perforated bottom 13, solid front and rear walls 14 and solid side or end walls 15, respectively. The upper or top of the tank B is open with the uppermost edge horizontally flush with the upper edge of the outer tank A.

Located within or nested in the interme-

mediate tank B is an innermost tank or separator body or frame C, the same being open at its top and bottom but is formed with solid front and rear walls 16 and solid end or side walls 17, respectively. The body or frame C is adapted to rest upon the wire mesh or perforated bottom 13 of the intermediate tank B as is clearly shown in Figure 1 of the drawings. In the nesting of the outer tank 10 A, intermediate tank B and separator body or frame C there will be presented therebetween liquid spaces 18 and 19 entirely about the intermediate tank B and said body or frame C, while the wire mesh or perforated 15 bottom C of the tank B will constitute a false bottom for the separator body or frame C as will be apparent and in view of the wire mesh character or perforated formation of said body 13, liquid introduced will flow 20 therethrough into said separator body or frame C as will be obvious.

Arranged in the same horizontal or transverse plane intermediate the open bottom and top of the separator body or frame C 25 is a series of spaced parallel rocking shafts 20, which are spaced an equi-distance apart and are journaled in the front and rear walls 16 of the body or frame C as is shown clearly in Figure 2 of the drawings. The front or 30 forward end of each shaft 20 is extended and bent to provide a crank 21 and these cranks of the shafts 20 are pivotally connected to a shiftable bar 22, common to all of the cranks for effecting the simultaneous 35 rocking of the shafts 20. Fixed to the shafts 20 are louvers or shutter 23 which are adapted to open and close with relation to each other on the rocking of the shafts 20, so that when the louvers or shutters are in 40 closed position they will shut off the upper portion of the body or frame C from the lower portion thereof and on the opening of the said louvers or shutters the upper portion and lower portion of the body or frame 45 C are in direct communication with each other for a purpose presently described.

Swingingly connected to the front wall 16 of the body or frame C is an operating lever 24, the latter being supported upon a pivot 50 25 suitably fastened in said front wall 16 and is extended upwardly beyond the open top area of the separator, while engaged in the bar 22 is a lug 26, the latter being extended into an elongated slot 27 formed in 55 the lever 24, whereby the latter will be positively connected with the bar 22, so that on the swinging of the lever 24 the louvers or shutters 23 can be opened and closed for the purpose presently described.

60 In the operation or use of the separator hereinbefore described a solution or liquid agent of alkali, with starch and calcium chloride, the solution being of Baumé test number 40 of three-tenths of one per-cent alkali, is introduced into the said separator,

when the tanks A, B and body or frame C are assembled or nested as heretofore stated, the level of the solution or liquid agent being varied to meet the fancy of the user of the separator. Now, on introducing a commodity, such as beans, peas, grains and seeds through the open upper end of the body or frame C into the liquid agent or solution, the good and poor grades of said commodities will be automatically separated by gravitation in the solution or liquid agent, it being understood, of course, that the louvers or shutters 23 will have been opened so as not to retard or effect a barrier for the gravitation of the commodity and in the process of separation the larger percentage of the imperfect commodity will be floated and the good or perfect grade of commodity will gravitate onto the bottom 13 of the tank B. Thereafter the shutters or louvers 23 will be closed, thus shutting off the graded commodity and on the lifting of the body or frame C from the separator the poor or inferior or imperfect grade of commodity can be extracted from the machine first, and thereafter the good or perfect grade of commodity confined within the tank B can then be removed from the machine or separator as will be clearly obvious. On the removal of the body or frame and the tank B the solution or liquid agent will not become agitated or unduly disturbed to alter the gravity characteristics of such solution or liquid agent. The solution or liquid agent of the Baumé test referred to is harmless in the use thereof for carrying out the method of separation of the commodity or in the operation of the machine hereinbefore described.

Furthermore it will be apparent that on removal of the tank B and the body or frame C from the outer tank A, the latter can be used continuously for the retention of the solution or liquid agent and this would permit of a maximum capacity of the separator as to the amount of commodity which could be separated and cleaned.

From the foregoing it is thought that the construction and manner of operation of the separator will be clearly understood, and therefore a more extended explanation has been omitted.

What is claimed is:—

1. A separator comprising an open top tank adapted to contain a gravitation solution for grading a commodity, a removable, open top intermediate tank positioned within and arranged in spaced relation with respect to the front, rear, sides and bottom of said other tank, said intermediate tank having a perforated bottom and adapted to receive a grade of the commodity being separated, the inner tank seated on said perforated bottom and arranged in spaced relation with respect to the front, rear and sides 125 130 135 140 145 150 155 160 165 170 175 180 185 190 195 198 199 200 205 210 215 220 225 - of the intermediate tank, said inner tank having an open top and bottom, a normally inactive combined separating and carrier means within said inner tank above the 5 lower end thereof, and operating means for shifting said separating and carrier means to active position to provide for the latter to perform its separating and carrying function.
- 10 2. A separator comprising a tank adapted to contain a gravitation solution for grading a commodity, a removable intermediate tank positioned within and arranged in spaced relation with respect to the front, rear, sides and bottom of said other tank, said intermediate tank having a perforated bottom and adapted to receive a grade of the commodity being separated, an inner tank having an open lower end seated on 15 said perforated bottom and arranged in spaced relation with respect to the front, rear and sides of the intermediate tank, a normally inactive combined separating and carrying means connected to the inner tank 20 and arranged in the latter above the lower end thereof, and means for operating said combined separating and carrying means to active position to perform a separating and carrying function.
- 25 3. A separator comprising an outer tank adapted to contain a gravitation solution for grading a commodity, a removable, intermediate tank positioned within and arranged in spaced relation with respect to the front, rear, sides and bottom of said outer tank, said intermediate tank having a perforated bottom adapted to receive a grade of the 30 commodity being separated, an inner tank having an open lower end seated on said perforated bottom and arranged in spaced relation with respect to the front, rear and sides of the intermediate tank, a normally inactive combined separating and carrying means within said inner tank above the 35 lower end thereof, and operating means for shifting said separating and carrier means to active position to provide for the latter to perform its separating and carrying function.
4. A separator comprising an outer tank adapted to contain a gravitation solution for grading a commodity, a removable intermediate tank positioned within said outer tank in spaced relation to the front, rear, sides and bottom of the latter and having a perforated bottom, a removable open bottom carrier seated on said perforated bottom and arranged in spaced relation with respect to the front, rear and sides of the intermediate tank, said carrier provided therein, above the bottom thereof with a normally inactive separating means for another grade of the commodity being separated, and actuating devices for shifting said separating means to active position to separate a different grade of the commodity separated from that of the grade selected by the intermediate tank.
5. In testimony whereof, I affix my signature hereto.
- CURRAN S. BENTON.
